SANITARY NAPKIN HAVING CONTROL ELEMENT WITH GEL-FORMING MATERIAL
Leon J. De Merre, Highland Park, N.J., assignor to
Johnson & Johnson, a corporation of New Jersey
Filed Feb. 12, 1965, Ser. No. 432,191
15 Claims. (Cl. 128—290)

This invention relates to absorbent products, and more particularly, is directed to improvements in sanitary napkins.

Absorbent products such as sanitary napkins usually consist of a core of one or more layers of highly absorbent, relatively dense fibers around which there is a fluid permeable, soft, knitted, woven or nonwoven wrapper. The core is conventionally made of layers of fibers such as carded cotton webs, air layered cellulosic fiber webs, comminuted wood pulp bats, tissue pulp or like materials which are highly absorbent. Also, sanitary napkins have been made with a fluid impermeable baffle sheet positioned within the wrapper. Conventionally, these fluid impermeable baffle sheets are of a plastic material most usually a sheet of polyethylene. These fluid impervious plastic baffle sheets are usually located on the bottom side of the highly absorbent fibrous core where any fluids which are not absorbed by the fibrous mass in the core are prevented from passing through to the wrapper overlying the bottom side of the pad.

By such a construction, sanitary napkins have been substantially improved in their ability to absorb large quantities of menstrual fluids while at the same time resisting "strike-through" and "side-spread failure." It has been primarily this "strike-through" and "side-spread failure" that has plagued napkin users. Accordingly, consumer demand has required considerable research effort directed toward solution of this most perplexing problem.

While the above-described plastic film barrier has proved to be the most effective solution to "strike-through" and "side-spread failure," other, even more effective means would be desirable. For example, sometimes napkins must be used during a period of time when they are subjected to excessive quantities of fluid. While the plastic film barrier initially prevents passage of fluids therethrough when sufficient quantities of menstrual fluids build up behind the fluid barrier, there is possibility of a spill over the longitudinal side edges of the fluid barrier where they extend upwardly over the sides of the absorbent core. In such instances, the menstrual fluids and solid or semisolid constituents thereof pass through to the wrapper covering the portion of the absorbent core which is away from the side positioned against the body of the user.

By the present invention, I have found a novel mechanism and means for substantially eliminating "strike-through" and "side-spread failure" in sanitary napkins and which also provides more effective absorption of menstrual fluids in the absorbent core portion of the napkin.

According to the present invention, I have provided a sanitary napkin having a menstrual fluid flow control element positioned in the absorbent core portion. The control element consists generally of one or more layers of normally highly absorbent fibrous or pulp material which is impregnated with one or more protein reactive agents which upon contact with fluids and proteinaceous materials forms a coagulum. By coagulation of the proteinaceous material in menstrual fluid, the coagulating agents constituting a portion of the control element are also effective to entrap the other nonproteinaceous components of the menstrual discharge and lock up or entrap the aqueous fluid phase. In essence, a barrier is formed in situ within the absorbent core portion of the sanitary napkin immediately upon interception of the control element by menstrual fluids. As the area of coagulum builds up, addi-

2

tional menstrual fluids impinging thereon spread laterally over the top surface of the control element forming additional coagulum thereby preventing penetration of fluids and proteinaceous constituents of menstrual fluids from passing therethrough. Additionally, any pool of fluid which might be formed at the top of the formed-in-situ impervious coagulum becomes semisolidified thus preventing leakage through the control element and spill over at the side edges of the formed-in-situ-coagulum barrier.

These and other features and attendant advantages of the present invention will be apparent from the description hereinafter contained when taken in conjunction with the accompanying drawings in which:

FIG. 1 is a perspective view of an absorbent sanitary napkin which is shown partially open to illustrate the incorporation of the invention, and

FIG. 2 is a cross sectional view taken on line 2—2 of FIG. 1.

Referring now to the drawings, a sanitary napkin 10 incorporating the invention includes a relatively thick, elongated absorbent core 12 enclosed within a liquid pervious wrapper 14 whose ends extend beyond the ends of the absorbent core to provide the usual attachment tabs 16. The absorbent core can be about 2½ inches wide and 8 inches long and can consist of one or more layers of fibrous material such as carded cotton webs, air-layer cellulosic fiber webs, comminuted wood pulp bats, tissue pulp or like materials which are highly absorbent. There can also be included within the absorbent core 12 one or more layers of semirepellent sheets such as sulfite, creped paper or absorbent layers of bleached sulfite paper wadding and the like. The entire core assembly is enclosed within a liquid pervious wrapper 12.

In the embodiment shown in the drawings, there is positioned intermediate the absorbent core 12 and the fluid pervious wrapper 14 on one side of the napkin, a fluid control element 18 which consists of a layer of fibrous material impregnated with protein reactive chemicals. The fluid control element 18, to be described in greater detail hereafter, is illustrated in the drawings in a so-called "one-way" napkin. That is to say, the positioning of the fluid control element intermediate the core and the wrapper at one side of the napkin is worn with the side opposite the fluid control barrier positioned against the body. However, it is to be understood that a so-called "two-way" napkin can be made in accordance with the present invention by positioning fluid control element 18 within the absorbent core so as to have highly absorbent fibrous material on both sides thereof. In this instance either side of the napkin can be positioned against the body of the wearer, and all the advantages of the invention are obtained.

It is preferred that fluid control element 18 extend transversely across the width of the core 12 and longitudinally the full length of the core 14. Additionally, fluid control element 18 can extend upwardly partially covering or completely covering the longitudinal side edges of core 12 in the "one-way" napkin. Alternatively, strips of fibrous material impregnated with the protein reactive chemicals of the present invention can be placed along and coextensive with the longitudinal side edges of the core 12 in abutting relationship to the control element 18 positioned interiorly of the core 12 in a "two-way" napkin. In this manner, side edge spill-over as well as strike-through of menstrual fluids and proteinaceous components therein is prevented.

Menstrual fluid control element 18 can consist of any suitable, absorbent material such as one or more plies of wood fiber pulp, cellulose wadding, regenerated cellulose sponge, absorbent creped tissue, fibrous woven or nonwoven webs or the like. Particularly preferred, is a wood pulp bat of Natchez fiber.

The protein reactive chemicals used in the present invention must be those which react with the proteinaceous constituents of menstrual fluids to form a coagulum. Protein precipitating salts while effective for forming a barrier to the passage of some of the proteinaceous constituents of menstrual fluids are ineffective as a barrier to the fluid constituents thereof. In fact, menstrual fluids with some of the proteinaceous constituents thereof removed by protein precipitating chemicals become less viscous and thereby pass more readily through the absorbent layers of the napkin on the side opposite to the precipitating chemicals.

I have found by using a protein reactive chemical which forms a coagulum the fluid constituents of menstrual fluids are also entrapped by the menstrual fluid control element. That is to say, the protein reactive chemical reacts with the proteinaceous constituents of menstrual fluids to form insoluble protein complexes which cannot be removed from the fluid carrier by dialysis.

When the menstrual fluid control element is intercepted by menstrual fluids, the protein reactive agents of the present invention react with the proteinaceous materials thereof to form the coagulum of the above-described protein complex and in which the fluid portion of the menstrual fluids is also entrapped.

The protein reactive chemicals which I have found accomplish the above-described results are phosphotungstic acid, tannic acid and sulfosalicylic acid, each an admixture with pectin. The fibrous elements forming the menstrual fluid control element are impregnated with a mixture consisting of the pectin and one or more of the above-named acids.

The amount of pectin and acid used in the fibrous control element ranges from about 12% to about 20% pectin and from about 0.3% to about 1% of the acid constituent based upon the weight of the fiber. Most preferred, is a fibrous element impregnated with about 15% pectin and about 0.5% of the acid.

In the preferred forms, three types of menstrual fluid control elements are prepared by forming dry homogenates each consisting of one of the following admixed constituents:

(a) Natchez fiber 84.5%; pectin 15%; phosphotungstic acid 0.5%.

(b) Natchez fiber 84.5%; pectin 15%; tannic acid 0.5%.

(c) Natchez fiber 84.5%; pectin 15%; sulfosalicylic acid 0.5%.

About 60 grains each of the above compositions are formed into bats approximately 2½ inches wide, 8 inches long, and $\frac{3}{16}$ of an inch thick. Each of the above-prepared bats are placed at the bottom of an absorbent core and enclosed within a fluid pervious wrapper of nonwoven material. Samples of each of the above-prepared napkins are subjected to clinical testing where it is found in every instance when menstrual fluid penetrates through the core of the napkin to reach the fluid control elements, immobilization of the menstrual fluid occurs at the top of the control elements in the form of a brownish coagulum and the portions of the napkins on the opposite side of the control elements remain dry. There can be found no trace of proteinaceous material or fluid at or near the cover portion of the sanitary napkin positioned on the bottom side opposite the control element.

Attempts to separate by dialysis the proteinaceous constituents from the coagulum entrapped by the control elements are unsuccessful.

As seen from the foregoing description and examples setting forth illustrative embodiments of the invention there is provided a napkin which is economical to make, which effectively prevents "strike-through" of fluid absorbed by the napkin, which prevents "side-spread failure" of the napkin and which effectively absorbs and retains menstrual fluids and the proteinaceous constituents thereof. It is apparent that variations, modifications and changes in the foregoing illustrative embodiments and

examples can be made while still remaining within the spirit and scope of the invention.

What is claimed is:

1. A sanitary napkin comprising a relatively thick elongated absorbent core, a liquid pervious cover around said core and a fluid control element positioned interiorly of said napkin, said fluid control element comprising a relatively thin layer of fibrous material containing in admixture pectin and an acid selected from the group consisting of phosphotungstic, tannic and sulfosalicylic acids.

2. The invention of claim 1 wherein said control element is positioned intermediate said absorbent core and said cover on the bottom of said napkin.

3. The invention of claim 1 wherein said control element is positioned interiorly of said absorbent core.

4. A sanitary napkin comprising a relatively thick elongated absorbent core, a liquid pervious cover around said core and a fluid control element positioned interiorly of said napkin, said fluid control element comprising a relatively thin layer of fibrous material containing in admixture from about 12 to about 20% pectin and from about 0.3 to about 1.0% of an acid selected from the group consisting of phosphotungstic, tannic and sulfosalicylic acids based upon the weight of the fibers in said control element.

5. The invention of claim 4 wherein said pectin and said acid are contained in said control element in an amount of about 15% and about 0.5% respectively based upon the weight of the fibers in said control element.

6. The invention of claim 4 wherein said control element is positioned intermediate said absorbent core and said cover on the bottom of said napkin.

7. The invention of claim 4 wherein said control element is positioned interiorly of said absorbent core.

8. A sanitary napkin comprising a relatively thick elongated absorbent core, a liquid pervious cover around said core and a fluid control element positioned interiorly of said napkin, said fluid control element comprising a relatively thin layer of fibrous material being substantially equal in width and length to the width and length of said absorbent core, and containing in admixture from about 12 to about 20% pectin and from about 0.3 to about 1.0% of an acid selected from the group consisting of phosphotungstic, tannic and sulfosalicylic acids based upon the weight of the fibers in said control elements.

9. The invention of claim 8 wherein said pectin and said acid are contained in said control element in an amount of about 15% and about 0.5% respectively based upon the weight of the fibers in said control element.

10. The invention of claim 8 wherein said control element is positioned intermediate said absorbent core and said cover on the bottom of said napkin.

11. The invention of claim 8 wherein said control element is positioned interiorly of said absorbent core.

12. A sanitary napkin comprising a relatively thick elongated absorbent core, a liquid pervious cover around said core, a first fluid control element comprising a relatively thin layer of fibrous material being substantially equal in width and length to the width and length of said absorbent core and being positioned interiorly of said napkin, second control elements comprising relatively thin layers of fibrous material positioned along the coextensive with the longitudinal side edges of said absorbent core, said first and second control elements containing in admixture from about 12 to about 20% pectin and from about 0.3 to about 1.0% of an acid selected from the group consisting of phosphotungstic, tannic and sulfosalicylic acids based upon the weight of the fibers in said control elements.

13. The invention of claim 12 wherein said pectin and said acid are contained in said control elements in an amount of about 15% and about 0.5% respectively based upon the weight of the fibers in said control elements.

14. The invention of claim 12 wherein said first control element is positioned intermediate said absorbent core and said cover on the bottom of said napkin.

15. The invention of claim 12 wherein said first control element is positioned interiorly of said absorbent core. 5
